OTHER PUBLICATIONS

Clorox, Green Works Bottle, from at least as early as Aug. 2008.

Primary Examiner—Stella M Reid
Assistant Examiner—Elizabeth J Oswecki(57) **CLAIM**

The ornamental design for a bottle, as shown and described.

DESCRIPTION

FIG. 1 is a perspective view of a bottle showing our new design;

FIG. 2 is a top plan view thereof;

FIG. 3 is a front elevational view thereof, a rear elevational view being a mirror image thereof;

FIG. 4 is a left side elevational view thereof;

FIG. 5 is a right side elevational view thereof; and,

FIG. 6 is a bottom plan view thereof.

The broken line showing of a pour spout and bottom portion of a bottle is included for the purpose of illustrating only and forms no part of the claimed design.
